UNITED STATES PATENT OFFICE

147,944

DESIGN FOR A BUREAU

Ferdinand Ziegler, Union, N. J.

Application January 3, 1946, Serial No. 125,263

Term of patent 14 years

(Cl. D33—19)

To all whom it may concern:

Be it known that I, Ferdinand Ziegler, a citizen of the United States and resident of Union, county of Union, and State of New Jersey, have invented a new, original, and ornamental Design for a Bureau, of which the following is a specification, reference being had to the accompanying drawing, forming a part thereof.

The figure is a perspective view of a bureau showing my new design.

The side not shown is the same as the side shown and the rear is plain, with no ornamentation.

I claim:

The ornamental design for a bureau, as shown and described.

FERDINAND ZIEGLER.
